UNITED STATES PATENT OFFICE.

JOHN M. MARSTON, OF BOSTON, MASSACHUSETTS.

DESIGN FOR FRAME FOR MACHINES.

Specification forming part of Design No. 6,985, dated October 7, 1873; application filed January 6, 1873.
[Term of Patent 7 years.]

To all whom it may concern:

Be it known that I, JOHN M. MARSTON, of Boston, Massachusetts, have invented a Design for a Frame for Machinery, of which the following is a specification:

My design is fully illustrated in the accompanying drawing; and consists of the parts *a* *b*, arranged as shown.

I claim—
The design for a frame for machinery, substantially as herein shown.

JOHN M. MARSTON.
